FREEZER STORAGE TRAY FOR COMESTIBLES OR THE LIKE

Robert L. Wiley, Lake Forest, Ill., assignor to SI Lite Incorporated, Chicago, Ill.

Filed Jan. 7, 1971, Ser. No. 104,841

Term of patent 14 years

Int. Cl. D9—03

U.S. Cl. D9—187

FIG. 1 is a perspective view of a freezer storage tray for comestibles or the like, showing my new design;

FIG. 2 is a top plan view thereof;

FIG. 3 is a bottom plan view thereof;

FIG. 4 is a cross-sectional view taken substantially on the line 4—4 of FIG. 2; and

FIG. 5 is a side elevational view thereof.

I claim:

The ornamental design for a freezer storage tray for comestibles or the like, as shown.
